HARRY G. GEISSINGER, OF NEW YORK, N. Y., ASSIGNOR TO GEISSINGER REGULATOR COMPANY, OF NEW YORK, N. Y., A CORPORATION OF NEW YORK.

ELECTROMAGNETIC VALVE.

1,049,845.

Specification of Letters Patent.

Patented Jan. 7, 1913.

Application filed September 15, 1910. Serial No. 582,233.

To all whom it may concern:

Be it known that I, HARRY G. GEISSINGER, a citizen of the United States, residing at New York, in the county of New York and State of New York, have invented new and useful Improvements in Electromagnetic Valves, of which the following is a specification.

My invention relates to electro-magnetically operated devices and more particularly to electro-magnetic valves, which are adapted to control the flow of steam or hot water to radiators. It is essential in valves of this character that the electric actuating coils shall be completely isolated from the steam or water and that the movable parts shall operate with as little friction as possible for the purpose of economy in the power required. It is also advisable to so arrange the valve that in case of any interruption in the electric service the valve shall be left in the "open" position and subject to manual control.

It is the purpose of my invention to provide a valve which shall possess all of the above features. The valve stem is free to move with practically no friction since I avoid the use of any stuffing boxes or packing. I have, however, provided a construction which involves no loose or rattling joints and permits of noiseless operation. My valve is adapted to be readily adjusted to standard valve bodies.

Other advantages will be apparent from the following description in connection with the accompanying drawings which represent in vertical cross-section one embodiment thereof.

The valve-casing 1, is provided with the usual seat 2, upon which the packing 3 of the valve disk 4 is adapted to rest when lowered into the closed position, the valve being normally spring-held in the "open" position.

The electro-magnetic actuating mechanism comprises a base member 6, provided with a tubular extension 7, screwing into the casing and secured in position by a lock-nut 8 and packing 9. The magnetic shell 12 inclosing the energizing coil 13, is provided with a depending hollow core 14 and has an annular flange 15 fitting over the flanged edge of the base. Within and projecting above the hollow magnet core is a non-magnetic tubular separator 16, closed

at its upper end and having its lower flaring annular base 17 bolted to the magnetic base member 6, the joint being made steam tight by means of a gasket 18. This tube 16 forms the guide for the plunger 20 of the magnet 60 and separates it magnetically from the core 14. A nut 22, screwing upon the upper projecting end of the separator tube, bears upon the top of the magnet shell 12 and clamps it firmly upon the base 6. 65

The plunger rests upon the upper end of the hollow valve stem 23, which bears upon the valve disk 4. A tubular guide and support 25 for the valve and valve-stem is threaded within the tubular extension 7. 70 A spring 27 having its lower end secured to the valve disk 4, passes through the stem 23 and is suspended from a pin 28, which passes through the slotted upper end of the stem and rests upon the top of the tubular guide 75 25. The spring yieldingly holds the valve in raised or "open" position and sustains the weight of the valve stem and plunger.

The operation of this valve will be understood from the foregoing description. Normally the valve is held in the "open" or raised position as illustrated. When the coil 13 is energized, the magnetic flux lines generated are caused to pass downwardly through the shell 12, flowing through the base 6 and converging in the central position where they jump across the intervening space to the plunger, completing the magnetic circuit by threading the gaps constituted by the non-magnetic separator 16 and 80 entering the core 14. It is evident that the magnetic flux will produce opposite magnetic poles 10, 10¹, in the lower plunger face and the opposite portion of the base and that the magnetic tension will draw the 90 plunger downwardly, forcing the valve disk against its seat in opposition to the force of the fluid-pressure and the spring 27. The parts are so adjusted that the lower portion of the plunger will occupy the dotted line 95 100 position and be held slightly out of contact with the base in order that there may be no tendency to adhere when the coil is deenergized. This adjustment is effected by raising or lowering the base member 6 in the 105 valve casing. The tension of the spring 27 may be altered by the height of the guide tube 25 within the tubular base extension 7. The electric connection with the coil may be made by means of binding posts 29, passing 110

- through the shell said posts being inclosed in a protective housing if desired. As soon as the coil 13 is deenergized, the spring 27 will immediately lift the valve and the parts 5 supported thereon, the upward shock being absorbed by the cushion 30. If the valve is attached to a radiator and is under the control of a thermostat, the electric energy will only be expended when it is necessary to 10 close the valve due to the use of temperature above normal. It will be observed also that in the event of an interruption of the electric service, the valve will be left in the "open" position and may then be manually controlled. For the purpose of closing the valve manually I provide a screw plug 31 in the top of the separator tube which may be forced down upon the plunger until the valve is seated. When the screw plug is in 15 the normal position, as shown, the packing 32 insures a steam-tight joint.

Engineers and others skilled in the art will appreciate the important advantages of this invention. I have provided a valve especially adapted for radiators which is exceedingly compact, practically noiseless, and in which the electric actuating coil is completely isolated, yet leaving the valve-piston or stem free to move without any friction 25 due to the restraint of packing. The base of the magnetic shell inclosing the actuating coil screws directly into the valve-casing and may be adjusted to any standard valves. By enlarging the lower end of the plunger and 30 producing an attracting magnetic pole of 35 corresponding area in the base of the magnetic shell, a very strong pull is produced upon the plunger.

It will be evident that various changes 40 may be made in the structure of parts which have been illustrated for the purpose of showing an embodiment of my invention without departing from the spirit thereof or the scope of my claims, which are:—

- 45 1. An electromagnetic valve comprising a valve casing having a valve seat, a valve disk, yieldable means for normally holding said disk in "open" position, means for adjusting the tension of said yieldable means, a 50 magnetic shell having a depending tubular neck threaded to said casing whereby said magnetic shell may be adjusted toward or from the casing, an energizing coil within the shell, and a plunger reciprocable within 55 said coil having a stem passing through said neck to actuate said valve disk, said plunger having an enlarged base cooperating with the base of the shell to form opposite magnetic poles when said coil is energized, 60 whereby the plunger is operated.

- 65 2. An electromagnetic valve comprising a valve casing having a valve seat, a magnetic shell having a depending tubular neck supported upon said casing, an energizing coil within said shell, a valve-disk having a

stem projecting through said tubular neck, a plunger reciprocable within said coil and having an enlarged base resting upon said stem, a tubular guide surrounding said stem and adjustably supported within said tubular neck, and a spring supported upon said guide and attached to said valve-disk, whereby the valve-disk, stem and plunger are 70 yieldingly held in raised position.

3. An electromagnetic valve comprising a 75 valve casing having a valve seat, a magnetic shell having a depending tubular neck supported upon said casing, an energizing coil within said shell, a valve-disk having a stem projecting through said tubular neck, 80 a plunger reciprocable within said coil and having an enlarged base resting upon said stem, a tubular guide surrounding said stem and adjustably supported within said tubular neck, a spring supported upon said guide 85 and attached to said valve-disk, whereby the valve-disk, stem and plunger are yieldingly held in raised position, and means for manually seating said valve-disk.

4. An electromagnetic valve, comprising 90 a valve casing having a valve seat, a valve-disk, a magnetic shell secured to said casing, a non-magnetic tubular separator within said shell, an energizing coil within said shell and surrounding said separator, a 95 plunger slidably mounted within said tubular separator, a valve-stem connecting said disk and said plunger, and means for yieldingly supporting said valve in raised position.

100 5. An electromagnetic valve, comprising a valve casing having a valve seat, a valve-disk, a magnetic shell secured to said casing, a non-magnetic tubular separator within said shell having an annular offset lower 105 portion forming a chamber over the central portion of the base of the magnetic shell, an energizing coil within said shell and surrounding said separator, a plunger slidably mounted within said tubular separator and 110 provided with an enlarged disk-like base within said chamber, and a stem extending between said plunger and said valve-disk.

115 6. An electromagnetic valve comprising a valve casing having a valve seat, a magnetic shell having a central tubular core and provided with a tubular neck threaded into said casing, a non-magnetic tubular member within said core projecting beyond said shell, a nut threaded upon said projecting portion and engaging the top of the shell, a valve-disk having a stem projecting through said tubular neck, and a plunger reciprocable within said non-magnetic member and resting upon said valve-stem.

120 7. An electromagnetic valve comprising a valve casing having a valve seat, a magnetic shell having a central tubular core and provided with a tubular neck threaded into said casing, an energizing coil within said 125

shell and surrounding said core, a non-magnetic tubular member within said core and projecting beyond said shell, said member being bolted to the base of said shell, a nut
5 threaded upon said projecting portion and engaging the top of the shell, a valve-disk having a stem projecting through said tubular neck, a plunger reciprocable within said non-magnetic member and resting upon said
10 valve stem, and means for normally holding

said valve-disk and plunger in raised position.

In testimony whereof I have hereunto set my hand in presence of two subscribing witnesses.
